(No Model.)

W. SENG.

TABLE LEAF SUPPORT.

No. 336,757.

Patented Feb. 23, 1886.

UNITED STATES PATENT OFFICE.

WENDELIN SENG, OF CHICAGO, ILLINOIS, ASSIGNOR TO AUGUST HEUER
AND HENRY BROCKSCHMIDT, BOTH OF SAME PLACE.

TABLE-LEAF SUPPORT.

SPECIFICATION forming part of Letters Patent No. 336,757, dated February 23, 1886.

Application filed August 31, 1885. Serial No. 175,732. (No model.)

To all whom it may concern:

Be it known that I, WENDELIN SENG, a citizen of the United States, residing at Chicago, in the county of Cook and State of Illinois, have invented certain new and useful 5 Improvements in Table-Leaf Supports, of which the following is a specification, to wit:

This invention relates to table-leaf supports; and it consists in the peculiar construction 10 and arrangement of the same, substantially as will be hereinafter more fully set forth and claimed.

In order to enable others skilled in the art 15 to which my invention pertains to make and use the same, I will now proceed to describe its construction and operation, referring to the accompanying drawings, in which—

Figure 1 is a section of a portion of a table 20 top and leaf with my device in use. Fig. 2 is a side view of the device folded; and Fig. 25 3 a similar view, partly in section, extended.

a represents the top, and *a'* a leaf, of a table 30 of any ordinary or preferred construction. To the leaf, and also to the table-frame, are secured at proper points small brackets *b*, *b'*, in each of which is hinged a metal rod, *b'*. One of these rods has secured upon its end a metal slide or sleeve, *b*, through which the other rod slides, as in the drawings. On one 35 side of the slide or sleeve *b* is cast a small frame, *c*, and a headed pin, *c'*, passes through this frame and the sleeve, as shown, which pin is formed with a shoulder, *c*, between which and the frame is a spring, *c*, which holds the pin in place. The other rod has near its outer 40 end a notch, *d*. When this leaf is folded, the spring-pin is pulled out to disengage it from the notched rod, and when the leaf is allowed to fall the slide passes down to the position 45 shown in Figs. 1 and 2. When the leaf is drawn out, the rods are extended till the spring-pin engages the notch *d* and the whole is firm and substantial.

It will be seen that the ends of the rod- 45 sections are turned at right angles to their

main portion and entered in the brackets to form the hinges, and this, together with the cast slide or sleeve, renders the device strong and cheap. The casting or sleeve is formed with a socket to be firmly secured on one rod, 50 and it will be seen that a thin web of metal is left between this socket and the passage through which the other rod slides, thus separating the rods and preventing any friction between them as they are operated. 55

I am aware that supports have been heretofore made in which a single arm is hinged on one part of the table and slides at the other end on a stationary guide on the other side of the table, and I do not desire to claim such as 60 my invention.

Having thus fully described my invention, what I claim as new, and desire to secure by Letters Patent, is—

1. In a table-leaf support, the combination 65 of a pair of supporting rods, each hinged in a suitable bracket, and one provided on its inner end with a sleeve and spring latch-pin, and the other formed with a notch, substantially as and for the purpose set forth. 70

2. In a table-leaf support, the combination of the rods *b'*, having their outer ends turned or bent at right angles and hinged in the brackets *b*, the sleeve *b*, cast with a frame, *c*, the shouldered and headed pin *c'*, the spring 75 *c*, and the notch *d*, substantially as and for the purpose set forth.

3. A casting for table-leaf supports, consisting of a main body, *b*, formed with a socket to receive one part of the support, separated by 80 a web of metal from a passage for the other part of the support, and having a guide-frame for the spring-latch cast or formed with it on one side, substantially as shown and described.

In testimony whereof I affix my signature in 85 presence of two witnesses.

WENDELIN SENG.
